MUSICAL STRING INSTRUMENT

Giuseppe Virzi, New York, N. Y.

Application August 11, 1938, Serial No. 224,245

5 Claims. (Cl. 84—277)

This invention relates to musical string instruments, and has among its objects the provision of an improved instrument of this character having improved adjustable means for producing and controlling the free sounding character of the instrument.

Another object of the invention is the provision of a device of the nature set forth having improved means whereby the bridge post can exert varying degrees of relatively cushioned pressure or a relatively hard pressure, as desired, for different sound effects.

Another object is to provide a string instrument having a post at the bridge provided with an expanding portion whose rotation shall not cause rotation of the post with the frictional cushioning portions of the latter.

Another object of the invention is to provide an instrument of the nature set forth having improved peg means for controlling the string tension of the instrument in an improved cushioned manner to permit free sounding but without a deadening effect on the instrument.

A further object of the invention is to furnish a device of the type alluded to having few and simple parts and which is inexpensive to manufacture and assemble, and durable, reliable and efficient to a high degree in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a plan view of a violin showing a device embodying the invention.

Fig. 2 is an enlarged transverse sectional view thereof taken on the line 2—2 of Fig. 1.

Fig. 3 is an enlarged fragmentary sectional view with parts in elevation showing a bridge post device embodying the invention.

Fig. 4 is a smaller fragmentary view of the bridge post device in a different position for exerting a hard pressure.

Fig. 5 is a sectional view of a bridge post element of modified construction.

Fig. 6 is a sectional view of a peg element according to the invention.

The advantages of the invention as here outlined are best realized when all of its features and instrumentalities are combined in one and the same structure, but, useful devices may be produced embodying less than the whole.

It will be obvious to those skilled in the art to

which the invention appertains, that the same may be incorporated in several different constructions. The accompanying drawing, therefore, is submitted merely as showing the preferred exemplification of the invention.

Referring in detail to the drawing, 10 denotes a string instrument such as a violin embodying the invention. The same may include the usual sounding chamber 11, neck 12, strings 13, secured by the tail piece 14, held in place by a peg 15, and the strings being adjustably tensioned by the pegs 16 of the neck. The strings 13 extend over a bridge piece 17 that rests on the upper wall 18 of the instrument body 11, which upper wall is furnished with sound openings 19. Between the upper and lower walls 18, 20 of the body 11, and supporting the former to take up the pressure of the bridge 17 is a post 21 embodying the invention.

The post 21 may be in the nature of an adjustably expandable device such as a turnbuckle. For example, it may include a tube 22, perforated at 23 for engagement by a screw or wire to rotate the tube 22 through a sound opening 19 in order to adjust the turnbuckle. Extending from the tube 22 are aligned right- and left-hand screw portions 24. Engaging the latter are the heads 25 which are thus moved toward or away from each other on operating the turnbuckle.

Each of the heads 25 may be provided with a cushioning element 26 which imparts the pressure of the post 21 on the adjacent wall of the sound chamber 11, and serves to yieldingly support the same but without deadening the vibrations of the sound chamber. For this purpose the elements 26 may consist of a fine grained leather, cork, fabric, or rubber, although I prefer to use cork. The latter may be suitably impregnated with an adhesive to moderate or otherwise control its yielding qualities. The pressure face of the element 26 may be covered with a member 27 of a fine sheet material such as leather or a textile fabric to prevent any crumbling of the cork.

Preferably the element 26 is of generally conoidal shape and is set into an opening 28 of generally similar shape. The purpose of this arrangement is to permit the yielding element 26 to be wedged into the opening 28 to a degree according to the increased pressure to which the post 21 is subjected. As the maximum pressure is approached, the element 26 is substantially entirely received in the opening 28 so that the wooden head 25 begins to contact or bear on the adjacent wall of the sound chamber as shown in Fig. 4, thereby affecting the vibratory qualities thereof. Such direct pressure of the heads 25 may be varied as desired. Upon relieving the pressure the cushioning elements 26 may move slightly outward of the openings 28.

It will be appreciated that the wooden sound chamber of a musical instrument is subjected to considerable stress due to various causes including temperature and humidity. Since the outer surface of the sound chamber is covered with varnish whereas the inner surface is not, the latter is readily influenced by climatic conditions, and hence the conditions at the different surfaces cause various slight bending and other stresses. Thus the musician may make adjustments to suit, not only as to temperature and humidity, but also with respect to the different vibratory and tonal effects that may be required from time to time.

The practicability of the invention resides to a large degree in the fact that the post 21 can be easily adjusted, and can be removed and replaced, all through the openings 19. In fact, this is the accepted way of periodically replacing bridge posts, in all violins. Certain musicians have the necessary tools for performing these operations without requiring the services of a violin mechanic. By using a turnbuckle, I have found that the adjustment is easily effected because the heads 25 will not turn. Any turning of these heads would result in lateral movement of the post 21 because the latter bears on inclined portions of the walls 18, 20 as shown in Fig. 2. The cushioning material is also of advantage in this respect because it grips the walls 18, 20 of the violin body so as to resist any tendency to turning.

In Fig. 5 is shown a modified head 29 which may be substituted for one or both of the heads 25. The same may have a conoidal cushioning element 30 mounted like that at 26, but having an integral pad portion 31 having a covering 32 like that at 27. This pad portion overlies the wooden head 29 and may be flat, but is preferably convexed so that the central area, supported by the part 30 has the most resilience. As the post pressure increases, the portion 31 comes into play to assume a large part of the stress, whereby varying cushioning effects may be produced.

In Fig. 6 is shown the peg 15 which affords a suitable limited degree of resilience or yielding quality under the constraint of the peg structure. Thus the latter includes a head 33 grooved at 34 to receive a strand for attachment to the member 14. Said head may have a conoidal stem 35, which receives a conoidal sleeve 36 of a cushioning material of the kind hereinbefore mentioned. Tightly fitted over the sleeve 36 is a metallic sleeve member 37 having an annular portion 38 spun inward into a groove 39 of the stem. Between the portion 39 and a wall 40 of the groove is a ring washer 41 of a cushioning material of the type hereinbefore set forth. The external surface of the sleeve 37 may be knurled or longitudinally grooved so as to be frictionally engaged with the violin body 11 when the sleeve 37 is forced into an opening thereof. Thus it is seen that the peg head 33 is wholly out of direct contact with the violin body and is in cushioned engagement with the same, the cushioning elements being under compression, particularly the former.

It will be understood that the pegs 16 may be constructed like that at 15, except that the sleeve 37 would be externally smooth for easy rotation and would be sufficiently long for proper mounting thereof and for receiving the strands 13.

It will thus be seen that I have provided a

musical string instrument which is free sounding in the body and in the mounting of the vibrating strands, and which fulfills the objects of the invention and is well adapted for practical use.

I claim:

1. A device including a sound post for the sounding box of a musical string instrument, the sound post comprising end heads and an intermediate turnbuckle for adjusting the length of the post, at least one head of the post having an axial inwardly tapered opening, said head having an element of generally porous elastic material wedged into said opening and projecting axially out of the opening to bear against an adjacent wall of the sounding box, the relative sizes of the element and said opening being such that the element is yieldingly movable inward and outward of said opening upon increasing and decreasing the pressure on the element.

2. A device including a sound post for the sounding box of a musical string instrument, the sound post comprising end heads and an intermediate turnbuckle for adjusting the length of the post, at least one head of the post having an axial inwardly tapered opening, said head having an element of generally porous elastic material wedged into said opening and projecting axially out of the opening to bear against an adjacent wall of the sounding box, said element being yieldingly movable into said opening with constantly increasing resistance upon increasing the pressure to which the element is subjected, and the depth of the said opening and length of said element being relatively such that the element is substantially entirely movable into the opening so that the outer end faces of the element and its end are substantially flush to permit the head to directly contact the wall of the sounding box.

3. A device including a post for the bridge section of a musical string instrument, said post being adjustable in length and having an end portion having an axial inwardly tapered bore, and a correspondingly tapered element of a generally porous resilient cushioning material, said element being set into said bore with its outer end projecting from the bore beyond the end portion of the post, said element being adapted to be wedgingly moved inward of the bore upon increasing the pressure to which the element is subjected with the element bearing against a wall of the sounding box.

4. A device including a post for the bridge section of a musical string instrument, said post being adjustable in length and having an end portion having an axial inwardly tapered bore, and a correspondingly tapered element of a generally porous resilient cushioning material, said element being set into said bore with its outer end projecting from the bore beyond the end portion of the post, said element being adapted to be wedgingly moved inward of the bore upon increasing the pressure to which the element is subjected with the element bearing against a wall of the sounding box, and the bore having sufficient size to substantially wholly receive the element under high pressure, so that both the element and the end portion of the post make contact with the said wall.

5. A device according to claim 3, wherein said material consists of finely grained cork impregnated with an adhesive.

GIUSEPPE VIRZI.
